his Atty.

United States Patent Office.

JOSEPH DILL, OF GRAND RAPIDS, MICHIGAN.

Letters Patent No. 104,943, dated July 5, 1870.

IMPROVEMENT IN TABLE FOR DOVETAILING-MACHINE.

The Schedule referred to in these Letters Patent and making part of the same.

To all whom it may concern:

Be it known that I, JOSEPH DILL, of Grand Rapids, in the county of Kent and State of Michigan, have invented new and useful Improvements in Machine-Tables; and I do hereby declare the following to be a full and correct description of the same, sufficient to enable others skilled in the class to which my invention appertains to fully understand and use the same, reference being had to the accompanying drawing which makes part of this specification, and in which—

Figure 1 is a plan view of my improved machine-table.

Figure 2 represents a piece of stuff, showing the manner of cutting the grooves on the table.

Figures 3 and 4 are detached views of the dovetailed guides.

Like letters of reference indicate like parts in the several figures.

The nature of my invention consists in a machine-table, constructed of two pieces connected to each other at the inner ends by bent pieces, in such a manner as to leave an open space between them, through which the saws of the machine may operate, the table being provided with peculiarly-shaped guides and rests, to adapt it especially to machines for grooving and dovetailing.

It also consists in dovetail-shaped guides, adjustable on the table, by means of which perfectly parallel grooves can be produced.

Fig. 1, in the drawing, represents the machine-table, consisting of two parts, connected to each other at their inner ends by upwardly-curved pieces, so as to leave an open space, S, through which the saw, or other grooving tools, may project when in operation.

Parallel with this slot, and at right angles to it, are formed a number of slots, d, in both sides of the table, which slots form the bearings for the adjustable rests R R' R' R'', and the adjustable gauges G G' g g'. The rests consist of pieces bent at right angles, their horizontal portion being provided with threaded bolts passing through slots d, and held on the under side of the table by means of nuts.

The gauges G G' are straight pieces, dovetailed downwardly, so as to fit into the dovetailed grooves as they have been cut. They are also adjustable by means of a bolt extending downwardly through slots d, and a nut.

Gauges g g' are pieces bent at right angles horizontally, their portions e being dovetailed, one upwardly and one downwardly.

B, in dotted lines in fig. 1, may represent a piece of stuff to be grooved, as shown in fig. 2.

The dovetail groove o, fig. 2, is first cut, and then slipped over gauge G', which has been adjusted to the proper distance from slot S to leave the desired space between groove o and the next one to be cut. The rests R and R' are then adjusted, and the operation continues.

As each groove has been cut, it is slipped over gauge G', thus insuring a perfect gauging of the distance between the grooves.

To cut the grooves t, fig. 2, the same operation is gone through with, the piece B resting against the rests R R', and the gauge G being used instead of G'.

In cutting parallel dovetailed grooves of great length, one of the great difficulties is to prevent the lateral motion of the stuff in which they are cut. I accomplish this by the gauges g g', slipping one end of the first groove cut over the end c of that gauge which is similarly dovetailed, and pressing the other end of the groove over the other gauge e, thus binding the pieces down firmly while the next groove is cut. In this manner any number of perfectly parallel grooves, of any desired length, may be cut.

Of course it is obvious that any and all of the rests and gauges may be changed to any of the slots d, as the necessities of the case may require.

Having thus described my invention,

What I claim as new, and desire to secure by Letters Patent, is—

1. The machine-table, constructed of two pieces connected to each other by curved pieces, so as to leave a central opening, S, when provided with slots d, rests R R' R' R'', and gauges G G' g g', all combined, arranged, and operating substantially as herein described.

2. The dovetailed gauges G G' g g', arranged to operate substantially as herein described.

Dated March 5, 1870.

JOSEPH DILL.
